UNITED STATES PATENT OFFICE.

JAMES H. MACKINTOSH, OF PATERSON, NEW JERSEY.

HEATER.

SPECIFICATION forming part of Letters Patent No. 256,345, dated April 11, 1882.

Application filed January 26, 1882. (No model.)

To all whom it may concern:

Be it known that I, JAMES H. MACKINTOSH, of Paterson, in the county of Passaic and State of New Jersey, have invented a new and useful Improvement in Heaters, of which the following is a full, clear, and exact description.

Reference is to be had to the accompanying drawings, forming a part of this specification, in which similar letters of reference indicate corresponding parts in all the figures.

Figure 1 is a side elevation, partly in section, of my improvement. Fig. 2 is a plan view of the same, partly in section through the broken line x x , Fig. 1. Fig. 3 is a sectional side elevation of a portion of the lower part of the same, taken through the line y y , Fig. 2. Fig. 4 is a side elevation of a portion of the upper part of the same. Fig. 5 is a sectional elevation of a part of the cold-air inlet-pipe. Fig. 6 is a side elevation, partly in section, of one of the air-heating flues. Figs. 7, 8, and 10 are sectional plan views of different forms of air-heating flues. Fig. 9 is a sectional elevation of a part of one of the air-heating flues, taken through line z z , Fig. 8.

The object of this invention is to promote efficiency in heaters, provide pure air, and facilitate the controlling of the heated air.

The invention consists in the air-heating flues provided with projections on the inner surfaces projecting alternately from opposite sides and extending beyond each other; also, in the air-heating flues having longitudinal slots or openings and provided with projections on their inner and extended surfaces; also, in the combination, with the heating flues provided with the projections on the outer surfaces, of the inclosing-case provided with projections on its inner surface; also, in the combination, with the case, the top and bottom plates, and the air-heating flues, of a pipe having a stop-cock, whereby the air that collects in the upper part of the water or steam space can be readily drawn off; and also in the combination, with the top plate and the perforated cover having dampers, of radial partitions and one or more pipes, whereby a part or all of the heated air can be used for heating other rooms, as will be hereinafter fully described.

A represents the outer case or shell of the heater, which may be made cylindrical or of

any other desired or convenient shape. Around the upper and lower ends of the case A are formed outwardly-projecting flanges, which are perforated to receive the bolts that secure the said case to the top and bottom plates, B.

In the top and bottom plates, B, are formed numerous round holes to receive the upper and lower ends of the air-heating tubes or flues C. The ends of the flues C are made round and are fitted air and water tight in the holes in the plates B. The bodies of the flues C may be made, round, oval, triangular, or of any other shape, as may be desired, or as the form to be given to the heater may render most convenient.

The flues C may have longitudinal slots or openings D formed through them, as shown in Figs. 6, 7, and 10, to increase the heating and heat-absorbing surfaces. For the same purpose the inner surfaces of the flues C can be roughened, or can have projections, E, formed upon them, as shown in Figs. 7, 8, 9, and 10.

Upon the outer surface of the heating flues C are formed outward projections, E', and upon the inner surface of the case A are formed inward projections, E'', which projections E' E'' greatly increase the heat-absorbing surface presented to the heating medium introduced into the space surrounding the flues C and enclosed by the case A, and thus increase the efficiency of the heater.

In the opposite sides of the case A are formed bulges F, to form spaces to receive the ends of the inlet-pipe G and the outlet-pipe H, which pass in through the bottom plate B, and through which hot water, steam, or other heating medium is introduced into the space around the flues C to heat the air passing through the said flues.

Air to be heated is introduced into the space below the bottom plate B through the flue I, leading from outside the building, and which is provided with a hinged damper or valve, J, opening inwardly. The damper or valve J is made of such a weight that as the air within the flues is heated and rises the pressure of the outside air will raise the said valve J more or less, and thus enter the heater, so that the supply of cold air will be regulated automatically by the amount of heat applied to the heater. When hot water or steam is used as the heat-

and in the space around the flues the air that may collect in the upper part of the space around the flues C can be drawn off through a small pipe, K, connected at its upper end with the upper part of said space, and connected at its lower end with the air-inlet flue I, or with a water-pan placed in the base of the heater. The water-pan is not shown in the drawings, as there is nothing new in its construction or use.

The pipe K is provided with a stop-cock, L, so that it can be opened and closed as required. When the cock is open the air in the upper part of the heater, being under pressure, will 15 counterbalance the atmospheric pressure in the inlet-pipe or water-pan, and consequently would be forced out of the said upper part through the said pipe.

The case A is placed upon a base, M, which is provided with a molding, N, to cover the bottom flange of the said case and the fastening-bolts, as shown in Fig. 1. The base M has a number of openings, O, formed through it, and is provided with sliding dampers P, 25 having corresponding openings, so that the air from the room can be admitted to the heater, heated, and discharged into the room without introducing outside air, when desired.

The top plate B of the heater is provided with a cover, Q, which may be arched, as shown in Fig. 1, or made flat, and which has numerous openings, R, formed through it to allow the heated air to escape into the room.

The perforated cover Q is provided with slide-35 dampers S, which are made in sections, so that more or fewer of the openings R can be covered, as desired. The middle part of the cover Q is supported by a solid or tubular standard, T, to which are hinged or pivoted a number of 40 radial partitions, U, which are so formed as to fit the space between the top plate B and the cover Q, as shown in Fig. 1.

The partitions U can be adjusted to divide the space between the top plate B and the 45 cover Q into two or more sections or compartments, with which are connected the inner ends of one or more air-pipes, V, so that by adjusting the sliding dampers accordingly a portion or all of the heated air can be sent through the

pipes V into other rooms, whereby several 50 rooms can be warmed from the same heater, if desired.

In Fig. 2 the dampers and partitions are adjusted to send the heat into three rooms—two 55 besides the one in which the heater is arranged; but it is evident that the number can be increased or decreased without departing from the nature of my invention. The cover Q is provided with a molding, W, for ornamentation and to cover the top flange of the case A and 60 its fastening-bolts.

Having thus described my invention, I claim as new and desire to secure by Letters Patent—

1. In a heater, the air-heating flues C, provided with the projections E on their inner surfaces projecting alternately from the opposite sides and extending beyond each other, substantially as and for the purpose set forth.

2. In a heater, the air-heating flues C, longitudinal slots D formed through them, and provided with the projections E on their inner surfaces and the projections E' on their external surfaces, substantially as and for the purpose set forth.

3. In a heater, the combination, with the 75 heating-flues C, provided with the projections E' on their external surfaces, of the inclosing-case provided with the projections E² on its inner surface, substantially as and for the purpose set forth.

4. In a heater, the combination, with the case A, top and bottom plates, B, and air-heating flues C, of the pipe K, having stop-cock L, substantially as herein shown and described, whereby the air that collects in the upper part of the 85 water-space can be readily drawn off, as set forth.

5. In a heater, the combination, with the top plate B and the perforated cover Q, having dampers S, of the hinged radial partitions U, 90 and one or more pipes, V, substantially as herein shown and described, whereby a part or all of the heated air can be used for heating other rooms, as set forth.

JAMES H. MACKINTOSH.
